(57) **CLAIM**

The ornamental design for a ground engaging tooth, as shown and described.

DESCRIPTION

FIG. 1 is a top, left perspective view of one embodiment of a ground engaging tooth showing our new design;

FIG. 2 is a bottom plan view thereof;

FIG. 3 is a top plan view thereof;

FIG. 4 is a left side elevational view thereof; with the right side elevational view being a mirror image of the left side;

FIG. 5 is a rear end view thereof;

FIG. 6 is a front end view thereof;

FIG. 7 is a top, left perspective view of a second embodiment of a ground engaging tooth showing our new design;

FIG. 8 is a bottom plan view thereof;

FIG. 9 is a top plan view thereof;

FIG. 10 is a left side elevational view thereof; with the right side elevational view being a mirror image of the left side;

FIG. 11 is a rear end view thereof;

FIG. 12 is a front end view thereof;

FIG. 13 is a top, left perspective view of a third embodiment of a ground engaging tooth showing our new design;

FIG. 14 is a top plan view thereof; with the bottom plan view being a mirror image of the top plan view thereof;

FIG. 15 is a left side elevational view thereof; with the right side elevational view being a mirror image of the left side elevational view;

FIG. 16 is a rear elevational view thereof; and,

FIG. 17 is a front elevational view thereof.

The phantom lines shown in various drawing figures form no part of the present invention.
